UNITED STATES PATENT OFFICE.

THOMAS G. HITT, OF SEATTLE, WASHINGTON.

SIGNALING-TORCH.

No. 836,381.

Specification of Letters Patent.

Patented Nov. 20, 1906.

Application filed September 6, 1906. Serial No. 333,526.

To all whom it may concern:

Be it known that I, THOMAS G. HITT, a citizen of Great Britain, (but having declared my intention to become a citizen of the 5 United States,) residing at Seattle, in the county of King and State of Washington, have invented new and useful Improvements in Signaling-Torches, of which the following is a specification.

10 This invention relates in general to pyrotechnic signals; and its object is to provide torches which may be conveniently and safely carried by ships at sea or by armies on land or by any other companies or persons to produce lights of various styles and colors for 15 signals.

To this end my invention consists in the construction and combination of parts forming a signaling-torch, hereinafter more fully 20 described, and particularly set forth in the claims, reference being had to the accompanying drawings, in which—

Figure 1 represents a side view of my invention in its normal condition, and Fig. 2 a 25 central longitudinal section of the same ready to be fired.

Numeral 3 represents a handle made of wood, which may be chambered at its upper end to carry a signal-star or fire ball 4, a fuse 5, and a charge of powder 6 to eject the star or fire ball. A casing 7 of strong paper is secured rigidly around the upper end of the handle and extends above it in tubular form as a receptacle for powders 8 9 10, each of which 30 may be composed of materials to burn with a different color. A firing-block 11 is secured in the upper end of the case 7 to carry a percussion-cap or primer 12 and a quick-match fuse 13, which communicates between the 35 cap 12 and the top charge 8 of powder. The firing-block 11 is longitudinally bored at 19 to receive a primer, and at the inner end of the bore the block 11 serves as an anvil for the primer to rest upon. The block 11 has a 40 transverse aperture 15, and below that are grooves 16 down its sides to receive the fuse 13. The firing-pin 17 is a separate piece normally carried in a socket 18 in the lower end of the handle, as shown in Fig. 1. The 45 mouth of the bore 19 is normally closed by a paper covering 20.

The operation is as follows: Take the firing-pin from its socket, push its point through the paper covering 20, then holding the 50 torch by its handle thrust it forward to force-

bly strike the head of the firing-pin endwise against some solid object. This drives the point of the firing-pin into the primer and explodes it, setting fire to the quick-burning fuse, and that ignites the first charge 8 of 60 powder. The plug and pin are thereby blown away and the signal-torch begins to burn. The powders 8, 9, and 10 or any other number similarly arranged set fire each to the next below. Then the fuse 5 is also 65 lighted and communicates with the star or fire ball 4 and the powder 5, which drives the fire ball up into the air. It will be understood that the charges of powder and stars or fire balls may be arranged to burn with any 70 color and in any order or number desired to produce signals according to any code or previously-agreed significance. Besides the established codes each company or ship may have signals peculiar to itself, and this signal-torch may be charged to suit all such conditions. It is easily carried, easily operated, and inexpensive. The primer being carried so deep in the firing-block it cannot be reached excepting by the firing-pin, and that being 75 normally carried at the other end of the handle, accidental explosion of this torch is rendered almost impossible. It is therefore safe both when stored away and when being handled. When a signal does not include a star 80 or fire ball, the chamber therefor may be omitted.

Having thus fully described my invention, what I believe to be new, and desire to secure by Letters Patent, is the following:

1. In signal-torches, the combination of a handle, a casing secured around and extending as a powder-receptacle above the handle; a firing-block secured in the upper end of the casing and vertically bored to receive a 95 primer and a firing-pin, and transversely bored and longitudinally grooved to receive a fuse; a firing-pin, and a socket in the lower end of the handle therefor.
2. In signal-torches, a handle chambered in its upper end and having in its lower end a pin-socket; a case around and extending as a powder-receptacle above the handle; a firing-block for the upper end of the case, the said block being longitudinally and transversely 100 bored and longitudinally grooved; and a firing-pin fitted to be stored in the aforesaid socket and to enter the longitudinal bore in the said firing-block, substantially as shown and described.

3. In signal-torches, a handle and a powder-chamber at its upper end; a firing-block in the upper end of the powder-chamber, the said block being provided with a deeply-located seat for a primer and a pin-hole leading to the seat and a fuse-passage leading therefrom into the powder-chamber; a separate firing-pin adapted to enter the firing-block, and a socket for the firing-pin located in the handle where the pin cannot communicate to with the primer-seat.
- In testimony whereof I affix my signature in presence of two subscribing witnesses.

THOMAS G. HITT.
